KNIFE SHARPENER

Frank R. Chester, Manhattan Beach, Calif.

Application September 4, 1944, Serial No. 552,605

6 Claims. (Cl. 76—85)

My invention relates to knife sharpeners which are adapted particularly to household use. In every household knives are used for carving meats and otherwise cutting food and other material. The cutting edges of such knives become dulled by use, and it is a specific purpose of my invention to provide a knife sharpener for restoring such edges. My invention can be used for other purposes, this use is described merely as illustrative of one way in which it can be used, and further objects and advantages will be obvious to one skilled in the art.

Referring to the drawing, which is for illustrative purposes only,

Fig. 1 is a view of a preferred embodiment of my invention as seen from above.

Fig. 2 is an elevation of this embodiment, the case which forms a supporting structure being shown in section.

Fig. 3 is a section on a plane represented by the line 3—3 of Fig. 2 as viewed in the direction of the arrows adjacent the line 3—3.

Fig. 4 is a side elevation of said embodiment.

Fig. 5 is a section through the helix.

The case or supporting structure 11 is preferably formed of sheet metal and is provided with feet or lugs 12 and 12a having holes 13 therein. Screws (not shown) may be used in the holes 13 to secure the case 11 to a shelf or board (not shown). Secured inside the case 11 at the left-hand side thereof, as seen in Fig. 2, is a stud 14 which is bored to receive a shaft 15, the other end of which is secured in the right-hand side of the case 11. Mounted rotatably and movable axially on the stud 14 is a cap 16, and mounted rotatably and movable axially on the shaft 15 is a cap 17. Secured in and between the caps 16 and 17 is a helix 18. This helix is preferably formed of a material that is somewhat harder than the knives to be sharpened and may be made of a trapezoidal strip as shown in Fig. 5. The outer corners 19 of this strip form sharp cutting edges.

Knives, however, may be sharpened by filing or rolling, and the helix may be of different cross section, for example, circular; the file teeth or corrugations may be placed on the sharpening surfaces; or, indeed, the knife edge may be improved by rolling between smooth surfaces on the helix.

Mounted about the shaft 15 is a compression spring 20, one end of which presses against the cap 17, and the other end of which presses against the end of the stud 14. This spring 20 tends to hold the helix assembly consisting of the helix 18 and the caps 16 and 17, which are

secured thereto, in its extreme right-hand position as shown in Fig. 2, or to return it to this position if the assembly is free to so move.

Where a relatively light helix is used, I may supply rollers 31 and 32, each of which turns on a shaft 33 secured at either end in the case. The helix 18 rolls and slides on the rollers 31 and 32. Other means of support may be used, for example, constraining the helix to move inside a cylindrical wall of the case 11.

Formed in the top of the case 11 is a groove 21 in which a knife 22, shown in dotted lines in Fig. 3, may be placed, the sides of this groove forming guides which hold the center of the knife blade in a plane to which the axis of the helix is perpendicular. The knife 22 may, however, be moved to the right or left as viewed in Fig. 3, in the directions of the arrows 23.

The method of operation is as follows: The case 11 being secured by screws to a shelf, table, or other support, the knife 22 is inserted in the slot 21 and is held down in contact with the cutting edges 19, and the knife is pulled back and forth in the directions of the arrows 23. This rotates the helix assembly so that the cutting edges 19 are moved over the sides of the knife, producing a sharp cutting edge having the angle P as shown in Fig. 2.

The device may be made quite small; in fact, for sharpening household knives the helix need not be over an inch in outside diameter. In a helix which has five complete turns and a diameter of one inch, each of the cutting edges 19 has a total effective length of about sixteen inches.

This device is sold under the name of "Rotary steel knife sharpener."

I claim as my invention:

1. A knife sharpener, comprising: a helix formed of material that is preferably harder than the material of the knives to be sharpened; and means for so guiding the knife that it can be moved through the helix in such a manner as to cause the sides of the knife to contact sharpening surfaces of adjacent turns of the helix.

2. A knife sharpener, comprising: a helix formed of material that is preferably harder than the material of the knives to be sharpened; means for so mounting the helix that it can rotate as the knife is pushed therethrough; and means for so guiding the knife that it can be moved through the helix in such a manner as to cause the sides of the knife to contact sharpening surfaces of adjacent turns of the helix.

3. A knife sharpener, comprising: a helix formed of material which is preferably harder

than the material of the knives to be sharpened, said helix being made of material having a cross section such that a cutting edge is formed on the outer corners of the turns of the helix; and a supporting structure for the helix, having guiding surfaces for a knife so placed as to cause the sides of the knife to be acted upon by said edge as the knife is moved through the helix.

4. A knife sharpener, comprising: a helix formed of material which is preferably harder than the material of the knives to be sharpened, said helix being made of material having a cross section such that a cutting edge is formed on the outer corners of the turns of the helix; a supporting structure for the helix, having guiding surfaces for a knife so placed as to cause the sides of the knife to be acted upon by said edge as the knife is moved through the helix; and means for so mounting said helix in said supporting structure that the helix can turn about the axis of the helix as the knife is moved through the helix.

5. A knife sharpener, comprising: a helix formed of material which is preferably harder than the material of the knives to be sharpened, said helix being made of material having a cross section such that a cutting edge is formed on the

outer corners of the turns of the helix; a supporting structure for the helix, having guiding surfaces for a knife so placed as to cause the sides of the knife to be acted upon by said edge as the knife is moved through the helix; and a shaft supported in said supporting structure, the helix being supported on said shaft so that it is free to turn and move axially thereon.

6. A knife sharpener, comprising: a helix formed of material which is preferably harder than the material of the knives to be sharpened, said helix being made of material having a cross section such that a cutting edge is formed on the outer corners of the turns of the helix; a supporting structure for the helix, having guiding surfaces for a knife so placed as to cause the sides of the knife to be acted upon by said edge as the knife is moved through the helix; a shaft supported in said supporting structure, the helix being supported on said shaft so that it is free to turn and move axially thereon; and a spring so placed as to resist axial movement of said helix on said shaft and to return said helix to its initial axial position on said shaft when said knife is taken out of contact with said helix.
